[57] **CLAIM**

The ornamental design for a fluorescent reflector lamp, as shown and described.

DESCRIPTION

FIG. 1 is a perspective view of the fluorescent reflector lamp illustrating my new design;

FIG. 2 is a front elevational view of the fluorescent reflector lamp of FIG. 1; and,

FIG. 3 is a bottom plan view thereof, wherein the top is dome shaped.

FIG. 1

FIG. 2

FIG. 3
